TRAIN DISPATCHING SYSTEM FOR
RAILROADSOscar H. Dicke, Rochester, N. Y., assignor to
General Railway Signal Company, Rochester,
N. Y.Original application April 2, 1927, Serial No.
180,475. Divided and this application August
3, 1929, Serial No. 383,227

10 Claims. (Cl. 246—3)

This invention relates to a train dispatching system in which the movement of trains is dispatched by wayside signal indications (or cab signal indications where cab signals are used) and more particularly to the control and indication mechanism, affording a large number of controls for governing or dispatching the train movements and affording a large number of indications for indicating the movement of the trains, employing a small number of line wires and circuits.

This application is a division of my prior application Ser. No. 180,475 filed April 2, 1927. It has heretofore been proposed in an application for patent filed by S. N. Wight Serial No. 120,423 filed July 3, 1926, to dispatch the movement of trains through the medium of manual control superimposed upon starting and entering signals at passing sidings of a single, or double track railway system, which starting and entering signals are controlled by track circuits and the like in accordance with traffic conditions ahead. This superimposed manual control permits such signals to clear only in accordance with traffic conditions, and affords means whereby any one or more of such signals may be held at stop. In said Wight application provision has also been made for safely operating a switch machine at a distant point in response to manual control means controllable by the dispatcher at a local tower. In the particular arrangement of the apparatus disclosed in said Wight application the direction in which traffic may move through the single track joining two passing sidings is determined by the sequence in which signals governing the entrance of trains into such single track section are cleared. That is, assuming that all the signals governing the entrance and departure of trains into or out of either end of a single track section are held at stop, and it is desired to set up east bound traffic, this may be accomplished in the Wight application by permitting clearing of the signals at the west end of the single track section first and then permitting clearing of certain signals at the east end of such single track section, in which event the starting signals at the west end of such single track section will clear, but the starting signals at the east end of such single track section will be held at stop. Obviously, this idea of controlling the direction in which traffic may move in a single track section by the sequence in which signals are cleared was resorted to by Wight in order to obtain additional controls without the need of additional line circuits, bearing in mind

that the distance between the dispatcher's tower and the passing siding in some cases is many miles. In the application of Wight there has also been disclosed means for giving indications as to changes of the occupancy of track circuits, as distinguished from means for continuously indicating the condition of occupancy of a track circuit.

In accordance with the present invention it is proposed to control the clearing of signals for the purpose of dispatching the movement of trains in a signal system as shown in the Wight application, to operate the switch machines, to receive continuing indications as to the position of each of the various switch machines, and to indicate continuously the condition of occupancy of various track circuits of a section of the railroad including a large number of passing sidings, all through the medium of a very few control circuits, some of which include the same or common return wire. Before mentioning the specific objects, purposes and characteristic features of the invention it is deemed expedient to first consider the problems encountered in endeavoring to reduce the control circuits for a system such as above mentioned. In the first instance it should be understood that it is difficult to control by a single means an exceedingly large number of signals independently of each other, remembering that certain trains may be desired to be held at stop while it is desired to allow many other trains to proceed. In the second instance, if it is desired to give indications as to the condition of occupancy of all of the track circuits of the railway system there is a possibility of not only a large number of track circuits being occupied at the same time but there is also a possibility of track circuits being entered upon at the same instant, so that it is very difficult to obtain simultaneous control as to the occupancy of these track circuits.

In view of the foregoing and other important considerations it is proposed in accordance with one form of the invention to provide a single line circuit which connects to a large number of synchronously rotated contacts, which contacts wipe over or otherwise close circuits to successive segments, these segments being connected to control suitable responsive means in such a way that if one of these segments at one location is energized a responsive means connected to corresponding segment at a distant point is energized as a result of the energy applied to the first mentioned segment. In other words, it is proposed to allot the use of the line circuit as to time to each of a

plurality of functions, this allotment of the line circuit being repeated once during each revolution of the synchronized contacts.

More specifically, it is not only proposed to energize a relay at a distant point through the momentary connection of this relay to a control lever as a result of the allotment of the line circuit as just mentioned, but it is further proposed to complete a stick circuit for such relay throughout the entire remaining period or cycle of operation of the synchronous contact. In other words, if the line circuit is allotted to a particular function for the first 50th part of a revolution of the synchronized contacts, a relay can be picked up at a distant point during this first 50th of a revolution, and with the relay once picked up a stick circuit is completed which will maintain the relay energized through the remaining 49/50th of the control cycle. In the particular embodiment of the invention disclosed in this application it is proposed to receive indications at the dispatcher's tower as to the condition of occupancy of track circuits and the positions the various switch machines are assuming at a particular time by the synchronized control arrangement above mentioned, and to control the various signals and switch machines located along the railway track by the train dispatcher from the tower through the medium of suitable code responsive selective devices. In this connection it should be borne in mind that the dispatcher is in a position to operate the various switch machines and clear the various signals or put them to stop one at a time at such time as he desires, so that there is no conflict due to simultaneous transmission of selected distinctive codes.

Other objects, purposes and characteristic features of the invention will appear as the description thereof progresses, and will in part be obvious from the drawings when taken in connection with the application of Wight above mentioned.

In describing the invention in detail reference will be made to the accompanying drawings in which:—

Figs. 1A and 1B show a train dispatching system in which the manual supervisory control that the dispatcher has over the various signals and switch machines is carried out through the medium of selective relays which may be selectively operated by distinctive selective code impulses, and wherein indications as to the operated position of the various switch machines and the condition of the various track circuits is indicated by a synchronized control arrangement such as shown in Figs. 1A and 1B; and

Fig. 2 is a side view of the essential elements of a selective relay responsive to a particular code only and specifically illustrates contacts capable of opening a circuit if a particular code of impulses is impressed thereon.

Fig. 3 shows a device such as illustrated in Fig. 2 except that it illustrates the parts capable of closing instead of opening a circuit; and

Fig. 4 shows a front view of the apparatus shown in Fig. 2.

Apparatus Figs. 1A and 1B.—Referring to Figs. 1A and 1B, and bearing in mind that the system shown therein is one wherein the outlying signals and switch machines are controlled from the dispatcher's tower DT, through the medium of code responsive means, and wherein indications are transmitted as to the operated positions of the various switch machines and the condition of occupancy of various track circuits to the tower,

all through the medium of one line wire one common return wire and associated mechanism whereby the use of the line wire is allotted as to time to a large number of functions. Referring to Fig. 1B in which there has been shown a single track section O, of a single track railway system, the passing siding N and a portion of the passing siding P. Although, the dispatching system embodying the present invention may be applied to double track railways signalled with any type of wayside signalling means, for convenience it is assumed that the signalling system shown is one of the absolute-permissive-block type such as shown in detail in the application of Wight mentioned. In the particular arrangement shown, the signals governing west bound traffic have been assigned reference numbers 1, 3, 5 and 7, as shown, the signals governing east bound traffic containing reference numbers 2, 4, 6 and 8, respectively, and the siding signals have been designated D with a prefix corresponding to that of the corresponding main signal.

Although the wayside signals illustrated are signals of the semaphore type, and although the starting and entering signals have been illustrated as two position signals, all of these signals are preferably three aspect signals, and may be either of the semaphore, the color light, position light or position color light signals, semaphore signals having been illustrated for convenience. In this connection it should be noted that the signals shown adjacent the track switch 1S and 8S, namely signals 1, 1D, 2, 2D, 7, 7D, 8 and 8D all have square blades, whereas the remaining signals have pointed blades, this distinctive configuration of the various blades is to conventionally illustrate that the signals 1, 1D, 2, 2D etc. are stop and stay signals which must not be passed unless one of the governing signals indicates proceed, and the intermediate signals 3, 4, 5 and 6 having pointed blades conventionally designate permissive signals which may be passed at low speed even though they indicate stop. The switches at the west end of passing sidings N and P have been designated 8S and the track switch at the east end of passing siding N has been designated 1S. These switches are preferably operated by suitable power operated switch machines, and these switch machines have been designated SMW and SME, respectively. Adjacent the switches 8S and 1S are contained fouling or detector track circuits of the usual construction, which are used to indicate the presence of a train on those parts of the main track and siding which conflict with each other, and these detector track circuits include track relays TW and TE, respectively. In addition to the starting signals 2 and 7 there are provided dwarf signals 2D and 7D which govern the movement of traffic off of the siding into the main track, and in addition to the entering signals 1 and 8 shown there are provided take siding signals or lower arm signals 1D and 8D for governing the movement of trains into the siding. Each of the various signals is controlled by a home relay designated H with a prefix corresponding to the reference number of the signal, that is the signals 2 and 2D are governed by the home relay 2H, and the position the switch machine SME is assuming, the signals 1 and 1D are governed by the 1H and the position the switch machine SME is assuming at the time; the signals 8 and 8D are controlled by the home relay 8H and in accordance with the position the switch machine SMW is assuming at the time, and the 75

signals 7 and 7D are governed by the home relay 7H and in accordance with the position the switch machine SME is assuming at the time. The switch machine SMW and the signals 1, 2, 1D and 5 2D at the east end of the passing siding N may be governed in accordance with the energization of the control relay ZE and in accordance with whether the signal 7 at the east end of the single track section O is clear or not, all in accordance 10 with the arrangement shown in the application of Wight heretofore referred to, and the signals 8, 8D, 7 and 7D and the switch machine SMW are controlled in accordance with the position of the control relay ZW and also depending upon 15 whether the signal 2 at the west end (not shown) of the single track section M is clear at the time all in a manner as explained in said Wight application. In this connection it is desired to point out that the control circuits for the signals 1, 1D, 20 2, 2D, 7, 7D, 8 and 8D are not exactly the same as those shown in the Wight application mentioned, partly because the control for the caution indication has been omitted and partly because a slightly different interlock between signals is employed, 25 and it is to be understood that the control circuits as shown in the Wight application may be used, if desired.

The system shown also includes an approach locking relay AL which may be controlled in the 30 same way as is the relay CR shown in the Wight application. This approach locking relay prevents the switch machine being operated in the face of an approaching train.

Referring more particularly to Fig. 1A of the 35 drawings in which a portion of the apparatus in the dispatcher's tower DT has been illustrated, the dispatcher's tower DT shows a miniature track layout including the passing siding N, a single track section O and a portion of the passing P. At the east end of the passing siding N has been shown an indicator comprising an indicating lamp TEL, which is controlled to continuously indicate the condition of occupancy of the detector track circuit including track relay 40 TE through suitable means more particularly described hereinafter. A similar indicating lamp TWL being provided at the west end of the passing siding N. Also, at the east end of the passing siding N of the miniature track layout are provided two lights preferably distinctive in color of which the light EN indicates, or is illuminated, when the track switch IS at the east end of passing siding N is in its normal position and the light ER indicates when this track switch is in its reversed or take siding condition, similar switch indicating lamps WN and WR being provided at the 45 west end of the passing siding N in the dispatcher's miniature track layout. The detector track circuit indicating lights TEL and TWL are controlled by indicating stick relays TEI and TWI, and the switch machine indication lamps EN—ER and WN—WR are controlled by polar stick relays SMEI and SMWI, respectively, in a manner as more clearly described presently.

The apparatus in the dispatcher's tower also 65 includes audible signals to inform the dispatcher as to the change in the occupancy of a track circuit, that is to say, a change in the indicating condition of any one of the lamps TWL, TEL, etc. In the particular arrangement shown the direct 70 current for energizing the lamps TWL, TEL etc. flows through a common wire including the primary winding of a transformer 50, the secondary winding of which transformer is connected in 75 series with the single polarized bell 51b having

two gongs of different tones, one of which sounds a single stroke upon an increase of current in the primary of transformer 50 and the other of which sounds similarly upon a decrease in this current. In other words, one bell sounds one tap, when current flows in one direction and the other bell responds when current flows in the other direction. Since the increase of current in the primary winding of transformer 50 causes current to flow in one direction in the secondary winding thereof and a decrease of current in the primary winding of transformer 50 causes current to flow in the other direction in the secondary thereof, one of the bells will sound when a lamp is lighted and the other bell will sound when an indicating lamp is extinguished. The bells are preferably distinctive in tone so that the dispatcher is distinctively audibly informed when a light is lighted and extinguished.

As heretofore mentioned the line wire 10W is 20 to be allotted with respect to time for serving a large number of different functions, and in order to have the line wire 10W complete the various independent circuits at different times it is proposed to provide contacts at the dispatcher's tower 25 and at various points along the railway for making such connections simultaneously. In order to accomplish this, it is proposed to rotate contacts carried by different shafts synchronously. Although these contacts may be rotated by synchronous motors having their field windings and rotor windings energized by alternating currents of different frequencies, may be rotated by suitable step by step mechanism, or may be rotated by motors, the particular arrangement shown in 30 Figs. 1A and 1B of the drawings employ alternating current motors of the self starting synchronous type. These synchronous motors SM preferably have a stator of the split phase type in which one of the phase windings includes a resistance unit 110, and the rotor is one of squirrel cage type in which the laminated core is constructed and shaped to form sufficiently pronounced poles so that when the motor has been brought up to substantially synchronous speed 40 45 the soft iron pole pieces of the rotor will fall in synchronism with the magnetic field, and the motor will then rotate at exact synchronous speed. The various synchronously driven shafts 14 are driven by the synchronous motors SM 50 through slip clutches 15, worms 16 and worm wheels 17 as conventionally shown. The lock magnets 111 of the system are connected directly in multiple, or across, the alternating current transmission line, so that the lock magnets are 55 normally energized, but are de-energized upon power failure, and the like. If power should fail on the alternating current transmission line 112 from which the various synchronous motors SM and lock magnets 111 receive their energy the 60 various lock magnets 111 will be de-energized and will allow the springs 119 to pull the stop pawls 113 containing rollers 114 to a position so that they engage the stop lugs 115 on the worm wheels 17. The movement of the stop arms 113 by the springs 119 is limited by the stops 116. It is therefore seen, that upon power failure all of the various contact arms of the synchronous system will be brought to a stop at exactly the same point in their operating cycle. 70 This provision is made so that upon re-energization of the transmission line 112, all of the motors will start to rotate their respective contact arms at the same point, and if these motors all have the same starting characteristics the time 75

required for them to reach their synchronous speed is the same, as is assumed and will be the case in practice, as a result of which all of the rotating contact arms will again rotate in synchronism even though there has been a power failure. Since all of the synchronous motors SM run at exactly the same speed the rotating contact arms will of course remain in synchronism after once synchronized. In other words, in the arrangement shown in the drawings the synchronous contact arms are rotated by motors which operate at exactly the same speed and provision has been made for bringing these contact arms in synchronism upon starting of the various synchronous motors.

Operation of Figs. 1A and 1B.—In order to get a more clear understanding of the apparatus conventionally illustrated in Figs. 1A and 1B it is deemed expedient to now consider the operation of the system. Before the movement of trains are considered in the operation of the system the position of the switch machines SME and SMW should first be ascertained as manifested by the indicating lights on the dispatcher's mature track layout. Figs. 1A and 1B should be laid end to end to illustrate the system. Referring to Fig. 1B it will be noted that the switch machine SME is assuming the normal position, and that with it in this position the positive side 30 of the battery 30 is connected to the stationary contact 31 of the synchronizing mechanism located at passing siding N. From this it will be seen that the moment the rotating arm 32 assumes a position to contact with the stationary contact 31 that the rotating contact 33 located at the dispatcher's tower DT is then in engagement with the stationary contact 34, so that, for an instant at least the positive side of the battery 30 is connected to the stationary contact 34 and in turn permits current to flow through the following circuit:—beginning at the plus (+) terminal of the battery 30, contact 35 of the switch machine SME, stationary contact 31 and movable contact 32 of the synchronizing mechanism located at siding N, line wire 10W, movable contact 33 and stationary contact 34 of the synchronizing mechanism located in the dispatcher's tower DT, through the winding of the indicating relay SMEI to the common return wire C connected to the midpoint of the battery 30. With this circuit momentarily completed the indicating relay SMEI is picked up closing its front contact and completing the following stick circuit:—beginning at the positive side of the battery 31 located in the dispatcher's tower, polar contact 36 of the indicating relay SMEI, front neutral stick contact 39 of this same relay, winding of this relay to the common return wire C, to the rotating arm 45 of the synchronizing mechanism located in the dispatcher's tower DT to the stationary contact 41 cooperating with the movable contact 45, back to the neutral point of battery 37. It may be pointed out here, that stick relays TWI and TEI may be stuck up by similar stick circuits to the one just traced but including batteries 37² and 37³, respectively. With this stick circuit completed the indicating relay SMEI is energized through the remaining part of the revolution, or until the rotating contact 33 again reaches the stationary contact 34. In other words, energy is transmitted from the distant passing siding N to the indication relay SMEI over the contacts 31 and 34 and the line wire 10W through a small fraction of one revolution 75 of the synchronizing mechanisms, and this indi-

cating relay is then stuck up for the rest of the revolution of the contacts 32 and 33, and so long as the contact 31 at the passing siding N is connected to the positive pole of the battery 30 the indicating relay SMEI in the tower DT will remain energized. With the indicating relay SMEI energized positively, that is, with its polar contact 13 to the right the normal indicating lamp EN is illuminated through the following circuit to indicate that the switch machine SME is in the normal position:—beginning at the terminal B of a suitable source of current, front contact 12 of the indicating relay SMEI, polar contact 13 in its right hand position, through the indication lamp EN back to the common return wire C connected to the other side of said source.

In the same manner as just described the indicating relay SMWI is picked up and stuck up through similar circuits and contacts which have been assigned the same reference numbers with distinctive exponents 1 (one). From this it will be seen, that in the same manner as just explained the relays SMEI and SMWI may also be picked up and stuck up in their reverse position when the switch machines assume the reversed or take-siding position, in which event the lamps ER and WR, respectively, will be illuminated. It is to be understood that during operation of the switch machines, such as SME, the battery 30 is not connected to the contact 31 and therefore the relay SMEI is deenergized while the synchronous contacts 33 assume a position to engage contact 34 (the stick circuit for this relay then being open at the gap in stick contact 41); so that, this relay SMEI will thereafter assume the de-energized position. In this connection, if desired, the stick circuits for the relays SMEI and SMWI may be omitted and the energization of the indicating lamps EN, ER, WN and WR may be controlled by the polar contacts 13 and 13¹ alone (with contacts 12 and 12¹ omitted), it being understood that the polar contacts of these relays remain in the position to which they were last actuated.

The control relays ZW and ZE located at the ends of the passing siding of the system, of which the passing siding N and a portion of the passing siding P only has been shown, control the switch machines and wayside signals in exactly the same way as described in the parent application. These control relays ZW and ZE are however controlled from the dispatcher's tower DT by different apparatus and in a different way than are those of the parent application. In the arrangement shown the relays ZW and ZE may be energized in the normal direction, in the reversed direction or may be de-energized in response to distinctive code impulses over the telephone line 117.

In order to describe the manner in which the control relays ZW and ZE are controlled from the dispatcher's tower it is deemed expedient to first briefly consider the operating characteristics of the code responsive selective relays SR conventionally shown in Figs. 2, 4 and 1B. Referring more particularly to Figs. 2 and 4 in which a code responsive selective relay SR has been conventionally shown which is of a construction such as shown in the patent to Geer and Leake No. 1,118,120 dated Nov. 24, 1914, and reference may be had to this patent as to the detailed construction of the code responsive selective relay used for controlling the various control relays ZE and ZW, and for ringing bells for the purpose of calling operators, train men or local ticket 75

agents to the telephone. The code responsive selective relay SR includes a polar armature which may be operated from its neutral to one or the other extreme position depending upon whether positive or negative current is caused to flow through its winding 118, so that if current flows in one direction (positive current) the armature is operated differently than if current flows in the other direction (negative current). The code responsive selective relay is so constructed that if it assumes its released or normal position the application of positive impulses through its winding will cause the arm 44 carrying a plunger 61 to be moved step by step one step for each impulse of positive current, through an arcuate path in a counterclockwise direction about the shaft 38. If now negative impulses are applied to the winding 118 of the selective relay SR the other arm 46 carrying a contact operator 62, which contains a piece of insulation 97, is caused to rotate in a clockwise direction about shaft 38. From this it readily appears that a specific number of positive impulses and a specific number of negative impulses will be necessary to bring both of these arms in a particular relation with stationary contacts arranged about a similar arc. If now the specific number of impulses applied to the winding 118 of the relay SR are of such a number as to bring the arm 44 in alignment with the contacts 126 (see Figs. 3, 4 and 1B), and then the necessary number of negative impulses are applied to this winding 118 to move the arm 46 in alignment with the same contact 126, the functioning of the interengaging mechanism of the selecting relay SR will be modified, in that after these arms 44 and 46 have been moved from their normal position the re-application of positive current to the winding thereof will not operate the arm 44, step by step, as it did heretofore, but will cause the plunger 61 to be pushed outwardly. The plunger 61 will continue to remain in its outward position so long as the positive current is maintained. With the plunger 61 positioned outward (see Fig. 2) it will cause the contact operator 62 to be swung about its pivot 64 thereby causing the insulating portion 97 to engage the stationary contact 126 and move it from engagement with the other stationary contact 126, and a circuit carried through contact 126 will be opened. Further, the selecting relay SR is of such construction that the arms 46 and 44 will be restored to their normal position when the positive impulse which operated the plunger 61 and followed the negative impulses discontinued. In other words, positive impulses operate the arm 44 step by step, negative impulses operate the arm 46 step by step, and then the application of a positive impulse will operate the plunger 61 and the discontinuation of this positive impulse will cause the arms 41 and 44 to be returned to their normal position. In substantially the same way as just described with respect to actuation of contacts 126 the arms 46 and 44 may be brought in alignment with the contacts 125, providing the requisite numbers of positive and negative impulses are transmitted in the proper sequence, which requisite numbers of impulses will of course be different from those necessary to bring these arms in alignment with the contact 126 just described. If the arms 46 and 44 are brought in alignment with the stationary contact 125 as just described, the application of positive impulses to the winding of the selecting relay SR thereafter will cause the contact operator 62 to force the contact 125 in engagement

with the other stationary contact 125 and complete a circuit so long as the positive current application is continued.

In order to make it more convenient for the dispatcher to operate the various neutral relays in response to various distinctive codes, suitable calling keys or control keys are preferably provided, and such control keys 140, 141, 142, 143, 144 and 145, and ringing keys 146, 147, 148 and 149 have been conventionally shown in Fig. 1A of the drawings. For a detailed description of the construction of these controlling and ringing keys, reference may be had to the patent to Geer and Leake No. 1,105,766 dated August 4, 1914.

Operation Figs. 1A and 1B.—Let us assume that the dispatcher located at the tower DT wishes to clear the signal 2 shown in Fig. 1B of the drawings, which if he wishes to do, he must energize the control relay ZE to its right hand position. In order to energize the control relay ZE to the right hand energized position the dispatcher will first be required to move the control lever LE (see Fig. 1A) located in the tower to the right hand dotted position so as to permit the use of the operating key 145. With the circuit completed so far as the control relay ZE is concerned the operator will operate the calling or control key 145 which will cause six positive impulses, followed by four negative impulses followed by one positive impulse to be transmitted. Referring to Fig. 1B it will be noted that the contacts 125 will be closed in response to a code consisting of six positive impulses and four negative impulses followed by one positive impulse. In other words, with the lever LE moved to the right hand position and the control key 145 operated at the dispatcher's tower, the contacts 125 at the passing siding N are closed, thereby completing the following circuit:—beginning at the positive terminal of the battery 150, wire 151, contacts 125 of the selective relay SR, wires 152 and 159, winding of the control relay ZE, wire 153, back to the neutral point of the battery 150. With this circuit completed the control relay ZE will be energized to the right hand position and will thereby close the following stick circuit:—beginning at the positive side of the battery 150, wire 154, polar contact 155 of the control relay ZE, wire 156, neutral contact 157 of the control relay ZE, wire 158, contacts 126, wires 152 and 159, winding of the control relay ZE, wire 153, to the neutral point of the battery 150. With the control relay ZE energized to the right hand position through the stick circuit just traced the signal 2 will assume the proceed position, assuming of course that traffic conditions in advance thereof are clear, all as readily understood from the drawings. It is of course understood that the contacts 125 of the selective relay SR were only held closed for a short time, sufficient to allow the control relay ZE to pick up, and that the arms 46 and 44 of the SR relay have been returned to their normal position. In practice the dispatcher will leave the levers LE and LW shown in Fig. 1A of the drawings in the position in which they were last used, and by so doing the position of these levers will inform him as to the energized or de-energized condition of the control relays ZE and ZW. Further it is to be understood that suitable indicators for indicating the sequence in which the levers for the ends of each single track section have been operated from their neutral position such as disclosed in said Wight application, may be used, if desired, which

If used will advise the dispatcher what direction of traffic movement has been set up in such single track section.

Let us now assume that the dispatcher located at tower DT wishes to put the signal 2 to stop. In order to do so, he will move his lever LE to its neutral normal position, in which position this lever LE permits the use of the operating key 144. If now, the dispatcher operates the key 144 a code consisting of seven positive impulses followed by three negative impulses followed by one positive impulse will be transmitted, and the transmission of these impulses will momentarily open the contacts 126 of the code responsive selecting relay SR located at the passing siding N. It should be noted that these contacts 126 are included in the stick circuit for the control relay ZE just traced, and that momentarily opening of this stick circuit will cause the control relay ZE to be deenergized, because momentary opening of this circuit will open the stick contact 157 after which reclosure of contacts 126 are not able to re-energize the control relay ZE.

Let us now assume that the dispatcher wishes to energize the control relay ZE to its left-hand energized position, in order to operate the switch machine SME to the reverse position and in order to clear dwarf signal 2D. In order to accomplish this he will be required to move his control lever LE to the left hand dotted position which position the control key 143 is in the circuit so that either positive or negative impulses may be transmitted from the battery 160 located in the dispatcher's tower. If now, the dispatcher operates the control key 143, five positive impulses will be transmitted followed by five negative impulses, followed by one positive impulse. This distinctive code will cause closure of the contacts 124 of the selective relay SR, and the closure of these contacts will cause the control relay ZE to assume the left hand energized position by reason of closure of the following circuits:—beginning at the negative terminal of the battery 150, wire 162, contact 124, wires 163 and 159, winding 45 of the control relay ZE, wire 153, back to the neutral point of battery 150. With the control relay ZE assuming the left hand energized position in response to the closure of the circuit just traced, a stick circuit for this control relay ZE is completed, which circuit is exactly the same as the stick circuit heretofore traced except that it includes the wire 164 instead of the wire 154. With the control relay energized to the reversed position the dwarf signal 2D may be caused to indicate clear through the closure of the circuit for this signal readily traced in the drawings. It is of course understood that the control relay ZE may be deenergized, and the dwarf signal 2D be caused to indicate stop by the train dispatcher 60 in the tower DT in response to movement of his lever LE to its middle neutral position and operation of control key 144, in a manner as already described.

In the same manner as just described with respect to the control relay ZE, the control relay ZW may be picked up and stuck up into the right hand position in response to operation of the control key 142, which transmits three positive impulses followed by seven negative impulses followed by one positive impulse, which closes the contacts 122, the relay ZW may be then dropped by opening the stick circuit thereof which includes the contacts 123, and which contacts are opened if the dispatcher operates the control key 141, 70 the operation of which transmits four positive

impulses followed by six negative impulses followed by one positive impulse; and the control relay ZW may be picked up to the left hand energized position and stuck up through the closure of contacts 121 of the code selective relay SR, which contacts are closed in response to operation of the control key 140, the operation of which transmits two positive impulses followed by eight negative impulses then followed by one positive impulse. It should be noted that the combination of impulses for each of the series of pairs of contacts has been designated by numbers having a prefix plus or minus as indicated in Fig. 1B of the drawings.

If the dispatcher should desire to call one of the train crew to a telephone 170 located adjacent the switch machine SME the dispatcher will move the lever L in the tower to a position to connect the calling key 148, will then operate the calling key 148 and thereby transmit eight positive impulses followed by two negative impulses and then followed by one positive impulse, which distinctive code will close the contacts 127 of the code responsive selective relay SR, the closure of which contacts will ring the bell 171 by connecting it in a closed circuit with the battery 172. The dispatcher may then communicate over the usual telephone apparatus including the telephone 173 at the dispatcher's tower and the telephone instrument 170 at the east end of siding N. 30 No provision has been made for calling the dispatcher to his telephone 173, because the dispatcher is supposed to be listening in on the line all the time, either through the provision of a head set or the provision of a loud speaker in the office, so that anyone along the line who desires to communicate with the dispatcher need only call into his phone the word "dispatcher" or some other suitable term and the dispatcher will reply. Since all of the control and ringing keys are 35 located in the dispatcher's tower there is no possibility of two codes being transmitted at the same time unless the dispatcher wilfully operates two keys at the same time which he is not supposed to do. Although in the arrangement 40 shown in Figs. 1A-1B only one line wire 10W has been illustrated, this line wire connecting the rotatable contact arm of each of the various synchronously controlled mechanisms located along the railway together, one arm being assumed to 45 be used at each important point along the railway, additional line wires may be used which connect with additional synchronously driven contact arms, in the event that there are more functions to be handled than can conveniently 50 be handled over one line wire through the length of time allotted to one rotation of the various synchronously driven shafts 14.

Having thus shown and described a specific embodiment of the present invention, it is desired to be understood that this has been done for the purpose of disclosing an application of the invention and in order to describe the invention rather than for the purpose of illustrating the exact apparatus preferably employed in 60 practicing the same or illustrating the scope thereof; and it is further desired to be understood that various changes, modifications and additions may be made to adapt the invention to a particular railway system whether single 65 track or double track and irrespective of the specific signaling system superimposed thereon, and that the synchronous and code responsive control systems may be used for operating switch machines irrespective of whether such switch 70

machines are used on a railway system employing a train dispatching system of the wayside signal indicating type, and that other changes may be made as the particular exigencies of the 5 case require, all without departing from the scope of the invention or the idea of means underlying the same except as demanded by the scope of the following claims.

What I claim is:—

- 10 1. In a train dispatching system of the wayside signal indicating type, the combination with a local office and a plurality of way stations, track switches and signals at each of said way stations, a detector track circuit associated with each of said track switches, and a selector system of the multiple distinctive code type wherein each code is characterized by a plurality of distinctive impulses for controlling said switches and signals in response to manual supervision 15 originating at said local office, and another selector system of the synchronous sequential indicating type for sequentially indicating the positions of said track switches and the occupancy of said detector track circuits, whereby codes 20 may be taken advantage of where manual supervision is available and sequential non-interfering communication is rendered available where changes at a plurality of locations occur automatically.
- 25 2. In a train indicating system, the combination with a selector type system for positioning contacts in a central office in accordance with traffic conditions at various points along a railway system, a plurality of indicators controlled by said contacts and rendered effective by electrical energization thereof, and means included in a circuit portion common to all of said indicators for sounding an alarm for each change in the total number of indicators active at one time.
- 30 3. In a train indicating system, the combination with a selector type system for positioning contacts in a central office in accordance with traffic conditions at various points along a railway system, a plurality of indicators controlled by said contacts and rendered effective by electrical energization thereof, and means for sounding one alarm for each increase and sounding a distinctive alarm for each decrease in the total 35 number of indicators active at one time.
- 35 4. In combination, a railway system including a distant track switch, a switch machine for operating said track switch, a polar control relay having a polar contact which remains in the last energized position thereof even if said relay has in the meantime been deenergized, a selector system of the code type wherein each series of transmitted impulses defines a particular code one for controlling each of a plurality of such polar control relays including said polar 40 relay over the same pair of line wires and each to a particular position by a distinctive series of code impulses, a normal operating circuit for said switch machine including said polar contact assuming one of its polar positions, a reverse circuit for said switch machine including said polar contact assuming the other of its polar positions, and a front contact of an approach locking relay which assumes its deenergized position when a signal governing traffic over said switch is at proceed included in both said normal and said reverse operating circuit.
- 45 5. In combination, a section of railway track including a track switch, a signal for governing traffic over said track switch, a switch machine for operating said track switch, a switch machine control relay, a signal controlling contact on said switch control relay controlled from a central office in accordance with the code character of a series of code impulses, a circuit for clearing said signal closed only if said track switch and said switch control relay assume corresponding positions and said signal controlling contact is closed, and means for preventing said switch machine being operated in response to a change in the position of said switch control relay when there is 50 a train approaching said track switch under proceed traffic conditions.
- 55 6. In combination, a railway system including a distant track switch, a switch machine for operating said track switch, a polar control relay having a polar contact which remains in the last energized position thereof even if said relay has in the meantime been deenergized, a selector system of the code type wherein each series of transmitted impulses defines a particular code one for controlling each of a plurality of such polar control relays including said polar 60 relay over the same pair of line wires and each to a particular position by a distinctive series of code impulses, a normal operating circuit for said switch machine including said polar contact assuming one of its polar positions, a reverse circuit for said switch machine including said polar contact assuming the other of its polar positions, and a front contact of an approach locking relay which assumes its deenergized position when a signal governing traffic over said switch is at proceed included in both said normal and said reverse operating circuit.
- 65 7. In combination, a section of railway track including a track switch, a signal for governing traffic over said track switch, a switch machine for operating said track switch, a switch machine control relay controlled from a central office in accordance with the code character of a series of code impulses, means for maintaining said switch machine control relay in its last actuated position, a signal controlling contact on said switch control relay controlled from a central office in accordance with the code character of a series of code impulses, a circuit for clearing said signal closed only if said track switch and said switch control relay assume corresponding positions and said signal controlling contact is closed, and means for preventing said switch machine being operated in response to a change in the position of said switch control relay when there is 70 a train approaching said track switch under proceed traffic conditions.
- 70 8. In combination, a railway system including a distant track switch, a switch machine for operating said track switch, a polar control relay having a polar contact which remains in the last energized position thereof even if said relay has in the meantime been deenergized, a selector system of the code type wherein each series of transmitted impulses defines a particular code one for controlling each of a plurality of such polar control relays including said polar 75 relay over the same pair of line wires and each to a particular position by a distinctive series of code impulses, a normal operating circuit for said switch machine including said polar contact assuming one of its polar positions, a reverse circuit for said switch machine including said polar contact assuming the other of its polar positions, and a front contact of an approach locking relay which assumes its deenergized position when a signal governing traffic over said switch is at proceed included in both said normal and said reverse operating circuit.
- 75 9. In combination, a railway system including a distant track switch, a switch machine for operating said track switch, a polar control relay having a polar contact which remains in the last energized position thereof even if said relay has in the meantime been deenergized, a selector system of the code type wherein each series of transmitted impulses defines a particular code one for controlling each of a plurality of such polar control relays including said polar relay over the same pair of line wires and each to a particular position by a distinctive series of code impulses, a normal operating circuit for said switch machine including said polar contact assuming one of its polar positions, a reverse circuit for said switch machine including said polar contact assuming the other of its polar positions, and a front contact of an approach locking relay which assumes its deenergized position when a signal governing traffic over said switch is at proceed included in both said normal and said reverse operating circuit.

- a train approaching said track switch under proceed traffic conditions, whereby said switch machine may be conditioned for a new position by operation of said switch machine control relay 5 but operation of said switch machine is deferred until the approaching train has passed over said track switch.
9. In combination, an office, a station, a section of railway track at said station including a 10 track switch, a signal for governing traffic over said track switch, a switch machine for operating said track switch, a switch machine control relay, a signal controlling contact on said switch control relay, a line circuit connecting said office and said station, means at said office for transmitting over said line circuit any one of a plurality of series of electrical impulses each 15 series comprising positive and negative impulses arranged in a pattern to define a code, code responsive means for distinctively controlling said control relay and said contact depending on the character of the particular code received, and a circuit for clearing said signal closed only if 20 said track switch and said switch control relay assume corresponding positions and said signal controlling contact is closed.

10. In combination, a section of railway track including a track switch, a signal for governing traffic over said track switch, a switch machine for operating said track switch, a switch machine control relay, a distant control office, a single circuit connecting said office and said section, a signal controlling contact on said switch control relay, means for transmitting from said office to said station over said line circuit any one of a plurality of series of electrical impulses each 10 series comprising positive and negative impulses arranged in a pattern to define a code, means distinctively responsive to certain of said series of impulses to control said switch machine control relay and said contact, a circuit for clearing said signal closed only if said track switch and said switch control relay assume corresponding positions and said signal controlling contact is closed, and means for preventing said switch machine being operated in response to a 15 change in the position of said switch control relay when there is a train approaching said track switch under proceed traffic conditions.

OSCAR H. DICKE. 25
